UNITED STATES PATENT OFFICE.

JULIUS DINHOFER, OF NEW YORK, N. Y.

DESIGN FOR A FINGER RING OR SIMILAR ARTICLE.

Application filed February 10, 1926. Serial No. 16,478. Term of patent 7 years.

To all whom it may concern:

Be it known that I, JULIUS DINHOFER, a citizen of the United States, and a resident of the city, county, and State of New York, have invented a new, original, and ornamental Design for a Finger Ring or Similar Article, of which the following is a specification, reference being had to the accompanying drawing, forming a part hereof, in which—

Figure 1 is a plan view of a finger ring or similar article showing my new design, and

I claim:

The ornamental design for a finger ring or similar article as shown.

JULIUS DINHOFER,
